UNITED STATES PATENT OFFICE.

STUART J. LEBACH, OF NEW YORK, N. Y.

DESIGN FOR A METAL BOX.

44,928.

Specification for Design.

Patented Nov. 25, 1913.

Application filed February 28, 1913. Serial No. 751,367. Term of patent 7 years.

To all whom it may concern:

Be it known that I, STUART J. LEBACH, a citizen of the United States, residing at New York city, in the county of New York and State of New York, have invented a new, original, and ornamental Design for Metal Boxes, of which the following is a specification, reference being had to the accompanying drawing, forming part thereof.

Figure 1 is a plan view of a metal box

showing my new design, and Fig. 2 is a front side view thereof.

I claim:

The ornamental design for a metal box, as shown.

STUART J. LEBACH.

Witnesses:

WILLIAM L. SCHWARTZ,

R. JACOBSON.
